UNITED STATES PATENT OFFICE

94,944

DESIGN FOR A TOY

Titus L. Bissell, Birmingham, Ala.

Application November 30, 1934, Serial No. 54,201

Term of patent 3½ years

To all whom it may concern:

Be it known that I, Titus L. Bissell, a citizen of the United States, residing at Birmingham, in the county of Jefferson and State of Alabama, have invented a new, original, and ornamental Design for Toys, of which the following is a specification, reference being had to the accompanying drawing, forming a part thereof.

In the drawing,

I claim:—

The ornamental design for a toy, substantially as shown.

TITUS L. BISSELL.
